SPOOL HOLDER

Gerardo Muccitelli, Brooklyn, N. Y.

Application March 28, 1957, Serial No. 45,476

Term of patent 14 years

(Cl. D3—19)

Fig. 1 is a front perspective view of a spool holder, showing my new design;

Fig. 2 is a side elevational view; and

Fig. 3 is a top plan view thereof.

I claim:

The ornamental design for a spool holder, substantially as shown.
